CLAIM

The ornamental design for a clip for use with a pacifier, as shown and described.

DESCRIPTION

FIG. 1 is a front perspective view of a clip for use with a pacifier, showing our new design;

FIG. 2 is a front elevational view thereof;

FIG. 3 is a left side elevational view thereof, the right side being identical thereto;

FIG. 4 is a rear elevational view thereof;

FIG. 5 is a bottom plan view thereof;

FIG. 6 is a bottom plan view thereof;

FIG. 7 is a front elevational view of a first modified form of FIG. 1, with the only difference residing in the appearance of the face and ear portions, all other undisclosed portions being identical to that shown in FIGS. 3-6;

FIG. 8 is a second modified form of FIG. 1, with the only difference residing in the appearance of the face and ear portions, all other undisclosed portions being identical to that shown in FIGS. 3-6; and

FIG. 9 is a third modified form of FIG. 1, with the only difference residing in the appearance of the face and ear portions, all other undisclosed portions being identical to that shown in FIGS. 3-6.
